Res. 1736

Frank Douglas, of Norwich, Conn.
Letters Patent No. 1736, dated March 17, 1863.

The schedule referred to in these Letters Patent and making part of the same.

To all whom it may concern:

Be it known that I, Frank Douglas, of Norwich in the County of New London, and State of Connecticut have invented or produced a new and original Design for a Skate; and I do hereby declare that the following is a full, clear and exact description of the same reference being had to the accompanying drawings making a part of this specification, in which:

Figure 1, is a side view of a skate, showing my design.

Figure 2, a transverse vertical section of the same, taken in the line v, v , Figure 1,

similar letters of reference indicate corresponding parts in the two figures.

A, represents the stock or foot-stand of the skate, and B, the runner which is of the "open" kind, that is to say, provided with knees or posts by which it is secured to the stock or foot-stand. This part of the runner, or rather this feature pertaining to its form constitutes no part of my design. The part of my invention or design which pertains to the runner consists in the shape of the front part a, thereof which extends upward with a gradual curve and is then bent backward and downward so as to project under the front end of the stock or foot-stand as shown at a, forming what may be termed a "swan neck" as shown in Figure 1.

The stock A, is of double curved form in its longitudinal profile, the front part b, having its upper surface of slightly concave form so as to cause the back end of said part to be somewhat more elevated than at its centre. The back part or heel c, of the stock is elevated at its front end at its junction with b, and the front end of c, and back part of b, are curved or rounded to form an arch-shaped elevation d, of the stock as shown clearly in Figure 1. The sides of the stock A, are rounded as shown at d, d, in Figure 2. The under surface of the stock or foot-stand corresponds in form to that of the upper surface with the exception only that

2

Ms. 1736

the under side of the front part of the stock or foot stand has a rather quicker curve as shown at c, so as to give a slight taper form to the toe thereof.

Having thus described my invention what I claim as new and desire to secure by Letters Patent, is: The configuration of the parts herein shown and described to form a new and original design for a skate.
